UNITED STATES PATENT OFFICE

MARION L. BROOKS, OF RANIER, OREGON

SCISSORS HONING AND CORRUGATING DEVICE

Application filed May 18, 1931. Serial No. 538,314.

My present invention has reference to a device for sharpening and corrugating the blades of scissors or shears, and is particularly directed to a means for holding the blade of such scissors or shears in a proper and rigid position to permit of the edge thereof being acted upon by a hone; and the object is the provision of a device for this purpose that is characterized by simplicity in construction, cheapness to manufacture, and reliability and efficiency in practical use.

To the attainment of the foregoing the invention consists in the improvement herein-after described and definitely claimed.

15 In the drawing:

Figure 1 is a side elevation of the improvement in practical use.

Figure 2 is a top plan view thereof.

Figure 3 is a sectional view approximately 20 on the line 3—3 of Figure 2.

Figure 4 is a sectional view approximately on the line 4—4 of Figure 2 and illustrating the manner in which the hone is guided when sharpening the blade of a shear or scissors by the improvement.

Figure 5 is a plan view of the supporting stud for the blade.

Figure 6 is a perspective view of the clamping member for the blade.

30 As disclosed by the drawing it will be seen that my improvement essentially includes a metal plate 1. The plate has its end at two of its opposite corners formed with right-angularly arranged extensions in the 35 nature of ears 2. These ears receive therein the offset ends of trunnions on the angle arms of a rod 3. The rod is bent to substantially U-shaped formation, and one of the trunnions 4 on one of the parallel arms 5 of the 40 said rod is headed and is engaged by a wing nut 6. The plate 1 is, at approximately the center thereof, provided with a transverse opening 7 which is of a length almost equaling the width, and the opening receives there- 45 in and has its side walls contacted by a lug 8 provided upon a cross sectionally round stud 9. The stud has a threaded bore that has screwed therein the threaded stem 10 of a winged head 11. Obviously by sliding the 50 stud through the slot or opening in the plate 1 and by screwing the bolt home the stud is held adjusted on the plate.

The plate is provided with a second trans- 55 verse slot or opening 12 of a less length than the slot or opening 7, the said opening 12 de- 60 signed to receive therein and have its side walls contacted by a lug 13 formed approxi- 65 mately centrally on the lower and right an- 70 gle flange 14 on one end of a metal block 15. The second end of the block is formed with a 75 lip 16 whose outer wall 17 is arranged at an 80 angle with respect to the block. As a matter- 85 of-fact the lip 16 is substantially V-shaped in 90 cross section and the body member 15 is pro- 95 vided with a threaded opening 18 for the 100 threaded shank 19 of a wind headed bolt 20. The shank 19 of the bolt passes through the slot or opening 12 and the member 15 affords a clamp for the blade of a pair of shears or 105 scissors as disclosed by both Figures 1 and 4 110 of the drawing. The stud 9 is adjusted to afford a rest for the outer and non-sharpened edge of the blade 21, and the clamp is ad- 115 justed to hold the blade approximately in a line with the upper edge of the plate 1. The 120 U-shaped rod is swung and through the me- 125 dium of the nut 6 is held adjusted at a de- 130 sired angle with respect to the plate 1 and the 135 rod affords both a rest and a guide for a 140 sharpening hone 22. By adjusting the lug 8 145 and the rod 3 the hone, which is preferably 150 of carborundum rock, is guided over the 155 beveled edge of the blade 21 at the desired in- 160 clination and the hone 22 is moved longitu- 165 dinally around the edge of the blade and 170 along the guide rod 3 so that a few reciproca- 175 tory strokes of the hone will effectively sharp- 180 en the blade 21 in an easy and expeditious 185 manner. If the blade is to be provided with 190 a corrugated edge a corrugated file is em- 195 ployed and the file, of course, is moved back 200 and forth against the edge of the blade until 205 the same is properly corrugated. In this 210 operation the guide rod 3 is, of course, prop- 215 erly adjusted and it is thought that the fore- 220 going description when read in connection 225 with the accompanying drawing will fully 230 and clearly set forth the simplicity and ad- 235 vantages of my improved device to those 240

skilled in the art to which such invention relates.

While I have illustrated one satisfactory embodiment of my improved device my features of invention are capable of extended application and I do not wish to be limited to the specific structure herein shown and described.

Having described the invention, I claim:

- 10 1. A sharpener for shear blades to be sharpened by a honing stone or to be corrugated by a corrugated file, comprising a plate, a supporting stud for the non-sharpened edge of a shear blade supported for lateral adjustment on the plate, a laterally adjustable clamp on the plate for holding the blade thereagainst, and a swingable substantially U-shaped hone guide member pivotally supported on the plate, and means engaging one of the pivots for said member for holding the member from swinging.
- 15 2. A support for the blade of a pair of shears to be sharpened by a honing stone, or to be corrugated by a file, and a guide for the stone or file, comprising a flat plate, having angle ears at two of the opposite corners thereof, a substantially U-shaped rod member having trunnion ends which are received through the openings and one of said trunnions being threaded, a binding nut engaging said trunnion, said plate having spaced transverse slots therethrough, a stud having a lug received in one of the slots and said lug contacting the side walls of such slot, a binding element engaging the stud, and said stud affording a rest for the non-sharpened edge of a shear blade, a clamp for the shear blade including a body portion having an angle edge formed with a lug to be received in the second slot of the plate and having its second edge formed with a lip which is substantially V-shaped in cross section and a binding element passing through said slot and engaging with the body of the clamp.
- 20 3. In testimony whereof I affix my signature.
- 25 4. MARION L. BROOKS.
